[57] CLAIM

The ornamental design for a lifting jack, substantially
as shown.

DESCRIPTION

FIG. 1 is a front perspective view of one end of a lifting
jack showing my new design;
FIG. 2 is a front perspective view thereof of the end
opposite to that shown in FIG. 1;
FIG. 3 is a rear elevational view thereof; and
FIG. 4 is a rear perspective view thereof.

FIG. 1

FIG. 4

FIG. 2

FIG. 3
